UNITED STATES PATENT OFFICE

2,593,321

SWIMMING APPLIANCE

Edward C. Lindgren, Maple Park, Ill., assignor of
one-half to Charles F. Dayton, De Kalb, Ill.

Application May 8, 1950, Serial No. 160,649

3 Claims. (Cl. 9—17)

1

This invention relates to a swimming appliance such as a so-called "kick-board" or other buoyant body adapted to float on water and support the forward end of a swimmer's body in an idle position while leaving the legs and feet of the swimmer free to practice kicking motions.

One object of the invention is to provide a swimming appliance of the above character which is constructed in a novel manner to support the swimmer's hands, arms, and shoulders below the level of the water in idle positions thus more closely simulating the natural swimming positions of these parts of the body than has been possible with prior appliances of the same general character.

Another object is to provide a novel appliance of the above character on which the swimmer may merely rest either one or both hands or feet without exerting any effort to hold onto the appliance or center the same in its natural floating position.

A more detailed object is to provide an appliance of the above character having a handle positioned on a buoyant body in a novel manner such that the weight of the swimmer's body with either one or both hands resting on the handle is applied in opposition to the buoyant force along the center of gravity of the buoyant body.

Other objects and advantages of the invention will become apparent from the following detailed description taken in connection with the accompanying drawings, in which

Figure 1 is a rear elevational view of a swimming appliance embodying the novel features of the present invention with some of the parts shown in section.

Fig. 2 is a perspective view illustrating the manner of using the improved device.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

The improved swimming appliance comprises generally a float or buoyant body 10 having sufficient buoyancy to support the head portion of a swimmer's body 11 and combined in a novel manner with a handle 12 suspended from the float substantially in the vertical plane of the center of gravity of the float and having a grip-

ping portion adapted to receive either one or both hands of the swimmer when the float 10 is spaced outwardly in front of the swimmer's head as shown in Fig. 2. While the float may take various forms, it is preferably inflatable so as to be collapsible for shipping and storing. For this purpose, the float comprises walls 13 and 14 of flexible material such as rubber or plastic sealed together along a seam 15 which extends completely around the float.

Preferably, the height, width, and length of the float are of approximately the same dimension. In any case, the length is such that the distance A between one end of the float and the center of gravity B thereof is substantially less than the length of the swimmer's arms 16 beyond his head so that when one or both of the swimmer's hands are resting on the handles 12, the end of the float is spaced from the swimmer's head as shown in Fig. 2.

The handle 12 is disposed horizontally beneath the float 10 and to receive either one of the swimmer's hands at the center as shown in Fig. 1 or both hands at opposite ends as shown in Fig. 2. To enable the float to remain centered in its natural floating position without any effort required by the swimmer when either one or both of his hands are resting on the handle, the latter is constructed so that the weight of the forward portion of the swimmer's body is always applied in opposition to the buoyant force along the center B of gravity of the float. For this purpose, the handle is supported substantially in the vertical plane of the center B of gravity as noted above with one gripping portion 17 of the handle along its center located beneath the center of gravity and left free to receive one hand of the swimmer while end portions 18 located on either side of the center portion are also free to receive the swimmer's hands. Preferably, these gripping portions 17 and 18 are rigid so as to retain their shape while supporting the swimmer's hands.

In the present instance, the handle 12 is a straight rigid rod suspended from the float by two members 19 which are connected to the float and depend therefrom for connection with the rod at points spaced along the latter to leave the central portion thereof free. To simplify the construction, the suspension members are preferably flexible flaps formed integral with the side walls 13 and 14 of the float along the seam 15 thereof and diverging downwardly away from the float. Washers 20 extend around the peripheries of eyes formed in the lower portions of the flaps to

reinforce the latter and receive opposite end portions of the rod. A spacer member 22, such as a tube of rubber or the like encircling the center of the rod, holds the flaps spaced apart to define the center gripping portion 17. The flaps are held inwardly against the ends of the spacer tube by coverings 23 on the end portions 18 of the rod, each covering in this instance comprising a tube of rubber or the like pressed over the end portions of the rod.

With a swimming appliance constructed as above described, a swimmer may support the forward portion of his body to practice kicking motions simply by laying his hands on the top of the handle 12 without the necessity of squeezing the latter. When a swimmer is resting either hand on the central portion 17 of the handle (see Fig. 1) or both hands on the end portions 18 (see Fig. 2), the hands, arms, and shoulders of the swimmer are completely submerged in the water just below the level of the latter owing to the location of the handle 12 below the water surface. It will thus be seen that the swimmer's hands, arms and shoulders are supported in an inactive position which closely simulates the active swimming position of the parts of the body. Since the handle lies substantially in a vertical plane through the center B of gravity of the float and is centered with respect to the latter, the weight of the forward portion of the swimmer's body is balanced on both sides of the center of gravity whether the swimmer is resting one or both hands on the handle.

The novel swimming appliance above described is versatile and may be used to support the swimmer's feet while practicing arm motions as well as to support the arms while practicing kicking motions. Thus, the swimmer's toes may be hooked over the end portions 18 of the handle 12 as in practicing the crawl stroke or the heels may rest on the handle while the swimmer practices the arm motions of the back stroke.

I claim as my invention:

1. A swimming appliance comprising, in combination, a buoyant body, a rigid elongated handle bar, a spacer member encircling the center of said bar and extending along the latter far enough to receive a swimmer's hand, two flexible flaps suspended from the center portion of the bottom of

said body and diverging downwardly away from the latter, said flaps having eyes therein to receive opposite end portions of said bar, and coverings on the end portions of said bar to hold said flaps against the adjacent ends of said spacer member, the end portions of said bar beyond said spacer member being long enough to receive and support the hands of a swimmer.

2. A swimming appliance comprising, in combination, a rigid bar, an inflatable body of flexible material having two flaps formed integral with the body and depending from the central portion thereof, said flaps diverging downwardly away from the body and having eyes therein receiving said bar, and a spacer on the center of said bar holding said flaps apart far enough to permit a swimmer's hand to rest on the bar between the flaps, the opposite end portions of said bar projecting outwardly beyond said flaps far enough to receive the hands of a swimmer.

3. A swimming appliance comprising, in combination, a buoyant body, an elongated handle bar, and supporting members connected to said body and depending therefrom when the body is floating on a liquid, the projecting end portions of said members being connected to said handle bar to support the same in a generally horizontal position below the level of said liquid and spaced apart along the bar to leave the central portion of the latter and the portions thereof adjacent the ends of the bar free and unobstructed to receive either one or both of either the hands or the feet of a swimmer.

EDWARD C. LINDGREN.
